UNITED STATES PATENT OFFICE.

CARL BUETZ, OF ZURICH, SWITZERLAND.

POTATO-LAYING MACHINE.

Application filed December 15, 1924, Serial No. 756,147, and in Switzerland December 22, 1923.

The present invention relates to potato-planting machines in which the potatoes to be conveyed advance automatically along a track.

For the purpose of obtaining a single file of potatoes in such a manner that each single potato has the necessary space for its forward movement which is dependent on its shape and size, it is necessary to eliminate surplus potatoes during the formation of the file and my invention consists in a mechanical conveying device arranged side-wise of the track to receive and remove potatoes which leave the track or the file being formed.

Tests have shown that the forming of a single row of potatoes in the manner mentioned is of great importance, since it prevents disturbances in the working process.

My invention also consists in other features of construction, combination and arrangement of devices hereinafter described.

The accompanying drawings illustrate an example of an embodiment of the invention and the way in which it may be carried out. In these drawings:—

Figure 1 shows an elevation, partly in section, of the potato-laying machine.

Figure 2 is a cross section through line 2—2 of Figure 1;

Figure 3 is a longitudinal section through line 3—3, indicated in Figure 1, and

Figure 4 represents a detail on a larger scale.

1 is a hopper or receptacle for the potatoes, this receptacle being provided with a laterally and obliquely disposed wall-plate 3 forming part of the base of the receptacle. Other parts serving to form the base consist of two boards or planks 1^a which incline from the two side-walls of the open receptacle towards the longitudinal center plane of the latter and the machine, these boards being attached to two longitudinally arranged beams 43. These beams are placed at some distance from each other and, declining rearwardly, are disposed at a suitable angle to the ground. Between the two longitudinally arranged beams 43 there is a fulcrum, as at 39, a swinging lever 23 with which, by means of linking rods 32 and 33, a stirring bar 2 extending through the

receptacle is connected. The swinging lever 23 receives its movement by means of a rod 8 linked to the forward end of the said lever, the rod 8 by the aid of a laterally arranged roller being adapted to engage with a cam groove 7 provided in a disk 7' mounted on the wheel axle 37 so as to be slidable thereon and rotatable therewith. 55 Connected with the disk 7' is a second disk 7" also formed with a cam groove which, upon a corresponding axial movement of the pair of disks 7', 7", may be made to co-operate with a second roller mounted on the starting rod 8, when the latter is disengaged from the disk 7'. The cam grooves of the said two disks, adapted in turn to be brought into engagement with the starting rod 8, are of different cam formations so that on making use of one or the other of the two disks a different number of lifts of the rod 8, during a complete rotation of the axle 37 to which the carriage wheels 10 are fixed is obtained. The disks 7', 7" are mounted 60 in a housing 6 attached to or forming part of the receptacle-base, the housing being centrally mounted between the wheels 10 and bearing on the shaft 37, and having a pivoted lid and also containing one of the chain wheels of a chain drive 26'. The purpose of employing the two disks 7', 7", for the cam grooves of different shapes, either one of which disks is adapted to be coupled to the rod 8, is to provide a means whereby, 65 as stated, a different number of lifts, or reciprocations, may be imparted to said rod for varying the number of working movements imparted to the lever 23. The two disks 7', 7" may be jointly shifted in one 70 direction or the other by a suitable shifter lever (not shown) mounted on housing 6, a movement of such lever in one direction throwing disk 7' into operation and disk 7" out of operation, while a movement of the lever in the opposite direction will throw disk 7' out of operation and disk 7" into 75 operation. The chain drive 26' is the means for the movement of two endless conveying chains 31 which possess a number of carriers 38 in the form of angle plates and are guided over two guiding wheels 26. Each chain 31 is arranged at the outer side of the adjacent beams 43 and is located in a casing 44

which may be partly uncovered. Above the beams 43 is a rearwardly projecting wall 1' slanting downwards and outwards from the receptacle to the lower lying end of the beams and thus in the direction of the corresponding chain 31, Figure 3. In the track or chute between the said beams a slidable tongue piece or reciprocating feeder 30, is arranged, said feeder being formed at that 10 end which passes under a cover plate in the receptacle, into a screen or grating which extends over a distance somewhat greater than the distance between the front face and the oblique wall plate 3 of the receptacle 1, 15 while this tongue piece or feeder from its other end is formed as a channel of curved cross-section. The slidable tongue 30 is under the control of a draw spring 29 and, by means of guiding rollers 25 and 27 and a 20 wire rope 36, is connected with the swinging lever 23. Above the sliding tongue are arranged, on a bar fixed to the wall 1' and carrying pivotally mounted lever arms, five 25 striking rollers 34, which are journaled in the ends of the said lever arms. The rear- 30 most of these rollers is pulled by a draw spring, which acts on its lever arm in order to pull the same in the direction of the sliding tongue 30, whereas the other striking rollers 34 with their carrying lever arms hang freely downwards.

A deflector and drag scoop or hoop 19 is fixed to the rear end of the swinging lever 23 by means of a bolt extending laterally 35 through the said lever. A stop plate 24 is pivotally mounted on the said bolt and the free end of the plate 24 is thickened for the purpose of forming a tilting axle for the throwing off of the potatoes. The plate 24 is ordinarily forced by an elastic spring 40 against the rear faces of the two beams 43. A rammer or stamper 28 cooperates with the tilting axle and is in the form of a lever having its end portions bent at right angles one of its end portions forming the 45 striker proper and its other end portion having a projection engaging the underside of the swinging lever 23.

The potato-laying machine is furthermore 50 provided with a plough 14 of hollow form which is suspended from the beams 43 so as to be turnable on a horizontal axis. Connected with a backwardly extending part 40 of the plough 14 are stilts or handles 21 by 55 which the machine is guided and of which each carries a rotatable disk or the like 22, the said handles being pivoted on an axle 15 mounted in a bracket 45 and supporting the end of the plow runner 40. The axle 15 also supports a lever 16, one arm thereof abutting against and cooperating with the 60 swinging lever 23, the other arm being linked to and carrying a striking bar 17 having a hoop-shaped head of semi-circular 65 form. The plough 14 has also attached to

it a forwardly extending arm 11, an adjusting screw S serving as an abutment for this arm and allowing of an angular adjustment of the plough 14. This adjustment regulates the depth of the furrow cut. 70

One of the two handles 21 is fitted with a lever with handle for moving a controlling rod 20 which, by means of a knee-shaped lever bearing on the axle 12 extending through the head of the plough 14, is 75 linked to the two forks 13. Each of these forks grip with their tines over the corresponding beams 43 and penetrates openings 80 in the oblique base part of the receptacle 1, so that they are situated in the conveying 85 track of the potatoes. By a corresponding movement of the controlling bar 20 the pair of forks may be moved upwards or downwards, in order to be more or less high above the base of the receptacle, the passing of the 90 potatoes thus being in a suitable measure blocked or rendered free for the regulation of the discharge of the potatoes to be conveyed.

Upon a forward movement of the machine 90 on the carriage wheels 10 the swinging lever 23, by means of the starting rod 8, is at suitable intervals swung up and down. The lever 23 then effects a to and fro movement of the stirring rod 2 provided with bends, which rod serves to loosen up the store of potatoes in the receptacle. By the swinging of the lever 23, the sliding tongue or reciprocatory feeder 30 is furthermore caused to be moved longitudinally to and 100 fro, since it is alternately moved by the said lever by means of the wire ropes 36 controlled by the draw spring 29, the said tongue then by a movement in the opposite direction of the swinging lever being moved backwards by the spring 29. Owing to the to and fro movement of the sliding tongue 30 the potatoes are automatically conveyed to the proper laying device and during the 105 conveyance they fall into the form of a row 110 or file to be delivered one after the other to the laying device.

The elimination of the too abundant potatoes from the row, so that eventually only 115 a single row or file of potatoes reaches the laying device and the separate single potatoes have sufficient room for the forward movement dependent on their form and size, takes place within the part of the potato- 120 conveying track or chute lying outside the wall plate 3 but inside the wall 1' of the potato containing receptacle and therefore before they reach the laying device proper. The short, but positive to and fro movement 125 of the sliding tongue 30 not only results in the forward movement of the taken up potatoes, but the reversing movement is particularly adapted to push out from the row small and badly formed potatoes, so that 130 they roll over the slanting upper side of

the corresponding beam 43 on to the conveying chain whence they are discharged into a box 5 where they are kept separate from the supply of potatoes in the receptacle 1. The striking rollers 34 touching the advancing potato-row or file smooth down the unsteady movements of the potatoes and attain thus their object, namely, to obtain a quiet advancing thereof. The foremost potato, when the rammer 28 in consequence of its own weight has been lowered below the plane of movement of the potatoes, will, owing to the corresponding position of the swinging lever 23, be made to abut against the stop plate 24 projecting above the head of the pair of beams 43. On the then following downward movement of the stop plate, caused by the corresponding movement of the swinging lever 23, the rammer 28, under the control of the said lever, executes with its arm turned towards the plate 24 an upward movement, whereby the arm gives to the potato lying in the track a knock, thus causing the potato to be knocked over the upper edge of the plate 24 serving as a tilting axle, and furthermore causing the potato to be thrown over to find its way into the furrow made by the plough during the forward movement of the machine. The springy bearing of the stop plate facilitates the safe throwing off of the arriving potatoes. In the aforementioned downward movement of the plate 24 the swinging lever causes the angle-shaped lever 16 to be swung about its axle or pivot at 15 in such a manner, that the striking bar 17 is carried a certain stretch along the ground, in order then to rest during the subsequent upward movement of the stop plate 24 in its position, for the purpose of preventing the rolling after of the potatoes falling between the hoop 19 and the striking bar 17 upon the ground. The hoop 19 draws the potato a short distance along the furrow until the hoop 19 is raised by the next upward movement of the rear end of the lever 23 which causes the hoop to pass over the potato. The potatoes are thus positioned at places approximately the same distance apart. The two disks 22 serve to carry the earth over the furrows and potatoes.

It will be understood that the afore-described elimination of too abundant potatoes from their conveying track is considerably facilitated by the outwardly slanting upper side of the pair of beams 43, Figure 4, as far as the same extends beyond the potato-containing receptacle 1. The potatoes eliminated from the tongue piece 30 in the formation of a single file are received by the conveying chains 31 direct from the said piece as they fall therefrom and are conveyed into the separate box 5 which is detachably mounted on the receptacle. If desired they, or some of them, can be again

placed into the receptacle 1, in order to be once more conveyed along the track in the manner described.

Of course means could be employed to convey potatoes from the box 5 to the receptacle 1.

Having thus described my invention, I claim:

1. A potato planting machine embodying a track, means for forming rows of potatoes and advancing the same automatically along the track, and a conveying device arranged to directly receive and remove potatoes which leave the track or the row of potatoes being formed in the track.

2. A potato planting machine embodying a track, means for forming rows of potatoes and advancing the same automatically along the track, and conveying devices at opposite sides of the track to receive the potatoes which leave the track.

3. In a potato planting machine, a hopper, a trackway, means for forming rows of potatoes and advancing the same along the trackway, means for leveling off potatoes traveling along the trackway, means for arresting the movement of potatoes traveling along the trackway, said last-named means being movable into and out of the path of the potatoes, and means for conveying to a suitable point of deposit potatoes laterally displaced from the trackway.

4. In a potato planting machine, a hopper, a trackway, feeding means for feeding the potatoes along the trackway, a reciprocating stirrer in the hopper, leveling means operating on the potatoes feeding along the trackway, a stop device for periodically arresting the movement of the potatoes, and means for periodically actuating the stirrer and projecting and retracting said stop device.

5. In a potato planting machine, a hopper, a trackway, a reciprocating feeder forming a portion of said trackway, a stirrer in the hopper, means for leveling off the potatoes passing along the trackway, a stop bar at the discharge end of the trackway movable into and out of the path of the potatoes, a striker for engaging and discharging the potatoes, and means for periodically operating the feed device, stirrer, stop bar and striker.

6. In a potato planter, a traveling vehicle having a hopper, an inclined chute for discharging potatoes from the hopper, feeding means for feeding the potatoes along the chute, means for leveling off the potatoes in the chute and discharging surplus potatoes laterally from the chute, a receptacle, and a conveyor at the side of the chute for receiving the surplus potatoes and conveying the same to said receptacle.

7. In a potato planter, a traveling vehicle having a hopper, an inclined chute for discharging potatoes from the hopper, feeding

means for feeding the potatoes along the chute, means for leveling off the potatoes in the chute and discharging surplus potatoes laterally at each side of the chute, a receptacle, and a conveyor at each side of the chute for receiving the surplus potatoes and conveying the same to said receptacle.

8. In a potato planter, a traveling vehicle having a hopper, an inclined trackway leading from the hopper, feeding means for feeding the potatoes along the trackway, means for leveling off the potatoes on the trackway and discharging surplus potatoes laterally from the trackway, a stop device at the lower end of the trackway for arresting the motion of the potatoes, and a knocker for releasing the potatoes held by the stop device.

9. In a potato laying machine according to claim 1 and having a feed receptacle, the provision in the rear part of the said receptacle of a fork, adapted to be projected into the track of the potatoes by means of a hand-operable lever and thereby stop the further passage of potatoes down the forward part of the track.

10. A potato planting machine according to claim 1, wherein a bar is fixed above the rear part of the track and has depending arms oscillatably mounted on it, the said arms each carrying a striking roller situated vertically above the track and adapted to act on the potatoes to assist in controlling the movement of the potatoes along the track and their discharge from the track.

CARL RUETZ.
